(57) **CLAIM**

I claim, the ornamental design for a table, as shown and described.

DESCRIPTION

FIG. 1 is a perspective view of a table showing my new design;

FIG. 2 is another perspective view thereof;

FIG. 3 is a front perspective view thereof, the opposite side being a mirror image thereof;

FIG. 4 is a top plan view thereof;

FIG. 5 is a side view taken from the right of FIG. 3; and,

FIG. 6 is a side view taken from the left of FIG. 3.
